UNITED STATES PATENT OFFICE.

THOMAS COX, OF GLOSTER, MONTANA TERRITORY.

MINER'S CANDLESTICK.

SPECIFICATION forming part of Letters Patent No. 347,691, dated August 17, 1886.

Application filed June 8, 1886. Serial No. 204,466. (No model.)

To all whom it may concern:

Be it known that I, THOMAS COX, of Glos-
ter, in the county of Lewis and Clarke and Ter-
ritory of Montana, have invented a new and
5 Improved Miner's Candlestick, of which the
following is a full, clear, and exact descrip-
tion.

My invention relates to that class of can-
dlesticks used by miners, and illustrated, de-
10 scribed, and claimed in my Patent No. 321,798,
granted to me on the 7th day of July, 1885,
the present invention consisting of an im-
proved mechanism for preventing the candle
from slipping out of its holder.

15 Reference is to be had to the accompanying
drawings, forming a part of this specification,
in which similar figures of reference indicate
corresponding parts in all the figures.

Figure 1 is a top or plan view of the can-
dlestick. Fig. 2 is a side view in partial sec-
10 tion. Fig. 3 is a cross-sectional view repre-
senting the socket in which the candle is held,
and Fig. 4 is an inverted plan view of a por-
tion of the candlestick.

20 The holder consists of a central socket, 10,
in which the candle is fitted, said socket be-
ing formed with or attached to a bar, 11, one
end of which is pointed, while the other is
made to constitute a handle, 12. To the up-
25 per end of the socket there is hinged a cover,
13, provided with a thumb-piece, 14, and this
cover is normally held closed by a spring,
15, arranged as illustrated. Upon one side
30 of the socket 10 there is a boss, 16, in which
there is secured a hook, 17, arranged as best
35 shown in Fig. 3. Upon the under side of
the bar, and just in front of the handle 12,
there is a downwardly-extending lug or pro-
jection, 18, that is centrally apertured, in or-
40 der to receive and guide a sliding pin or
catch, 19, the forward end of which projects
45 through an aperture formed in the lower por-
tion of the socket 10, the point 20 of the pin
19, which extends through the socket, being
of less diameter than the main body of the
pin. Just back of the point 20 there is ar-
45 ranged a finger-piece, 21, that is held against
the shoulder formed by the meeting of the
point 20 with the main body of the pin 19,
50 said finger-piece being held in position by a
pin, 22, that is passed through an aperture
formed in the point 20. A spiral spring, 23,

is arranged about the pin 19, and tends to
force the pin to the position in which it is
shown in Fig. 4; but from the construction 55
described it will be seen that the point 20 may
be withdrawn from its extended position with-
in the socket to the position in which it is
shown in Fig. 2, and when so withdrawn a
candle, 30, may be placed within the socket, 60
the cover 13 being forced back at this time to
the position in which it is shown in full lines
in Fig. 2.

Too great a retraction of the point of the
pin 19 is prevented by a stop, 24, formed upon
65 the bar 11, and located as clearly indicated in
the drawings.

In using the candlestick the pointed end of
the bar 11 is thrust into the heading or other
proper place; or, if more convenient, the can-
dlestick may be suspended by means of the
hook 17. The cover 13 is provided in order
70 that should the candle burn down within the
socket the cover will close and extinguish the
flame, thus preventing the candle from burn-
ing down too low and thereby heating the
socket, so that the body of the candle will melt,
75 and so melting drop out and ignite any dry
material that might be lying about.

Having thus fully described my invention,
80 what I claim as new, and desire to secure by
Letters Patent, is—

1. The combination, with a miner's candle-
stick having a socket, of a movable locking-
pin extending transverse to said socket, with
85 its forward end entering said socket, substan-
tially as set forth.

2. A miner's candlestick comprising the
handle, the attaching device, the vertical
socket, and the transversely-sliding spring-
actuated pin extending at its forward end into
90 the socket, substantially as set forth.

3. A miner's candlestick comprising the
handle 12, point 11, intermediate socket, 10,
apertured transversely, as described, the lug
95 18, apertured in alignment with the socket-
aperture, the pin 19, sliding in said apertures,
and having a finger-piece, 21, and the spiral
spring 23 on the pin between the finger-piece
and lug 18, substantially as set forth.

THOMAS COX.
